UNITED STATES PATENT OFFICE.

MICHAEL L. HOUTS, OF ST. LOUIS, MISSOURI.

DESIGN FOR A BOTTLE.

SPECIFICATION forming part of Design No. 16,331, dated October 13, 1885.

Application filed July 20, 1885. Serial No. 172,158. Term of patent 7 years.

To all whom it may concern:

Be it known that I, MICHAEL L. HOUTS, a citizen of the United States, residing at St. Louis, in the State of Missouri, have invented and produced a new and original Design for Bottles, of which the following is a specification, reference being had to the accompanying drawings, forming part thereof.

Figure 1 is an elevation of my newly-designed bottle. Fig. 2 is a side view of same, half in section. Fig. 3 is a vertical section of same on line 3 3 of Fig. 4. Fig. 4 is a horizontal section of same on line 4 4 of Fig. 1, these four views being deemed necessary to fully illustrate my design.

Heretofore bottles have been made which presented when viewed in elevation, as in Fig. 1, a thin flat bottom with abrupt edges and an oval outline or periphery. In these the oval shape extends from the bottom E to the neck of the bottle F.

The leading feature of my design consists in a raised or "struck up" panel surface, the outlines of which are shown when viewed in elevation, as in Fig. 1, or in horizontal section, Fig. 4. The body of my improved bottle has four paneled sides with beveled or chamfered edges and a chamfered bottom.

Similar letters refer to similar parts throughout the several views. 30

A represents my newly-designed bottle. B is the front or back panel, which is flat in its general contour, and extends entirely over the front or back of the bottle, having the pointed upper termination at the base of the neck F. 35 C C are the side panels, extending from the chamfered bottom E upward and over the shoulder, terminating at the base of the neck F. Each panel is finished with a beveled edge, D, extending from the bottom E of the bottle 40 to the base of the neck F.

Having thus described my design, I claim—

The design for a bottle herein shown and described, the same consisting of the raised front and back panels, B, having a pointed upper termination, the raised side panels, C C, 45 the beveled edges D, and chamfered bottom E.

In testimony that I claim the foregoing I have hereunto set my hand this 15th day of July, 1885.

MICHAEL L. HOUTS.

In presence of—
U. G. GOOD,
L. W. ZELIFF.
